CURTAIN STRUCTURE

Ralph D. Barker, Brentwood Heights, Calif.

Application October 6, 1933. Serial No. 692,398

3 Claims. (Cl. 156—25)

This invention relates to curtain structure and more especially to that class of curtain structures commonly known as roller shades.

The word curtain where used hereinafter is intended to mean curtains and shades attached to a lifting roller on which the curtain sheet will be coiled during the shade lifting action.

It is an object of the present invention to provide an improved ventilating curtain shade and 10 more especially to provide improved details of construction of the sheet and its roller whereby to prevent fluttering and undue wear of the top edge of the shade sheet, and further to provide for the smooth coiling of the shade sheet upon the 15 roller.

The invention consists in certain advancements in this art as set forth in the ensuing disclosure and having, with the above, additional objects and advantages as hereinafter developed, and 20 whose construction, combination and details of means, and the manner of operation will be made manifest in the description of the herewith illustrative embodiment; it being understood that modifications, variations and adaptations may 25 be resorted to within the scope, principle and spirit of the invention as it is more directly claimed hereinafter.

Figure 1 is a front elevation of the improved shade.

30 Figure 2 is a cross section of shade roller on line 2—2 of Fig. 1.

Figure 3 is a front elevation and partial section of a fragment of an upper portion of the suspended shade.

35 Figure 4 is a perspective showing an applied marginal reinforcement on the top margin of the curtain sheet.

Figure 5 is a perspective of the top edge backbone stiffening strip.

40 In its illustrated embodiment the curtain consists of a shade sheet 10 of any desired material and particularly of such a material as will smoothly coil upon a roller 11 of any conventional spring roller type of operation.

45 The shade 10 is shown as being connected by flexible strap suspenders 12 to the end portions of the roller 11; the flexible strap 12 being disposed beyond a longitudinal groove or channel 13 suitably formed and in the present case shown as 50 produced between longitudinal edges 14 of a segmental layer 15 applied to the roller core 11; this being an economical mode of providing the channel or groove 13 along the body of the roller 11.

The straps 12 are of thin durable material such as linen tape.

A further feature of the present shade resides in a stiffening construction along its top edge and to which the suspenders 12 are attached in 60 spaced relation rather near the end corners of the shade sheet so as to provide a substantially unobstructed draft opening below the roller and above the top of the pulled-down curtain. To secure the desired strength and stiffness along 65 the top of the shade and to prevent its fluttering and undue weaving under draft pressure a layer of fabric material 16 of any suitable kind is suitably affixed to the upper transverse marginal portion of the sheet 10 and this is adapted to be 70 folded on the line a—b so as to provide a folded top margin of desired depth along the shade. While this two-ply fold forms four layers of material and gives ample tensile strength, it is 75 desirable to further increase the transverse stiffness of the top of the shade and this is accomplished by applying over the folded top a metallic inverted channel strip 17 which will constitute a substantial backbone further increasing the 80 top marginal strength and amply stiffening the 85 top of the curtain to preclude fluttering and distortion weaving.

An additional feature resides in the provision of a longitudinal bar 18 laid within the fold of the reinforcing material 16 and about which the lower ends of the strap suspenders 12 are securely 90 attached by means of a strap bight 12a, Fig. 3. To permit the ready attachment of the straps, the several layers of the sheet 10 and the strip 16 are perforated as by longitudinal apertures 19 of a width sufficient to receive the straps 12 and likewise the backbone 17 is provided with strip 95 openings 20.

It will therefore be seen that the backbone 17 and the strap bar 18 cooperate to stiffen the top 95 edge of the shade sheet and provide for substantial attachment of the straps 12.

In operation of the device, when the curtain is to be rolled, the first action is the coiling of the straps 12 on themselves for a few turns about the ends of the roller 11 and then the backbone 17 along the top of the shade registers with the channel or groove 13 and rests substantially flush therein so that as the curtain sheet coils upon the winding roller the sheet will roll up in a 105 smooth manner.

What is claimed is:

1. A ventilating shade curtain structure including a curtain sheet having a stiffened top edge, and a roller provided with a longitudinal 110

groove for reception of the stiffened edge so that the curtain will coil on the roller smoothly.

2. A ventilating shade curtain structure including a curtain sheet having a stiffened top edge, and a roller provided with a longitudinal groove for reception of the stiffened edge so that the curtain will coil on the roller smoothly, and spaced flexible, suspenders connected to the top edge of the curtain sheet and to said roller;

10

whereby the curtain is positioned below the roller when unrolled therefrom.

3. A shade curtain roller having a longitudinal groove, suspender straps attached to the roller, beyond the groove ends, to coil thereon, and a curtain sheet to the top of which the straps are attached; the top of the sheet having a stiffening means received in said groove.

RALPH D. BARKER.
